United States Patent

Des. 237,428
Patented Nov. 4, 1975

237,428

HANDCUFF HOLDER

Roy L. Baker, Rte. 1, Box 245,
Magnolia, Ark. 71753

Filed Apr. 1, 1974, Ser. No. 456,910

Term of patent 14 years

Int. Cl. D2—07

U.S. Cl. D2—381

FIG. 1 is a front elevational view of a handcuff holder showing my new design, the dash lines indicate stitching;

FIG. 2 is a top plan view thereof;

FIG. 3 is a bottom plan view;

FIG. 4 is a side elevational view, the other side being a mirror image thereof; and

FIG. 5 is a rear elevational view.

The dashed lines indicate stitching.

I claim:

The ornamental design for a handcuff holder, substantially as shown and described.
